R. W. BELSON.

Domestic Boiler.

No. 9,766.

Patented June 7, 1853.

UNITED STATES PATENT OFFICE.

R. W. BELSON, OF PHILADELPHIA, PENNSYLVANIA.

BOILER FOR COOKING-STOVES.

Specification of Letters Patent No. 9,766, dated June 7, 1853.

To all whom it may concern:

Be it known that I, R. W. BELSON, of Philadelphia, in the county of Philadelphia and State of Pennsylvania, have invented 5 an Improvement in Culinary Boilers, and that the following is a full, clear, and exact description of the principle or character which distinguishes it from all other things before known and of the usual manner of 10 making, modifying, and using the same.

In describing my improvement in boilers for stoves, I will premise that I am aware that such boilers have for some years been provided with an escape tube, to conduct the 15 steam and odors into the chimney or flues of the stove, and that my present invention is an improvement upon such boilers. When the tube is open into the boiler, before the boiling commences, the smoke from the stove 20 is apt to pass into the boiler. This occurs whenever the draft of the stove is feeble, or a great amount of fuel is thrown on to the fire at once, or when the cover is suddenly raised; and when the cover of the boiler is 25 off, the smoke may escape into the room. To obviate these defects, I employ on the top of said tube a valve, so constructed and arranged, that, it may be controlled by the movements of the cover of the boiler, so that 30 when the boiling commences, and the cover is tightly in place, the valve shall be lifted from its seat, and the tube open for the escape of the steam. When the cover is entirely removed, the valve is closed by its 35 own weight. If the cover is placed lightly on, as it may be before boiling commences, then the valve may be only slightly open; or if the cover is placed unevenly on, the side or edge next the valve being raised up, then

the valve will be closed entirely; and as soon as steam begins to form, and the odors escape into the room, then the cover must be shut down closely, and the valve will be opened accordingly. All this will be readily comprehended by reference to the drawings, 45 in connection with the following brief description.

Figure 1, is a sectional elevation; Fig. 2, a top view.

In Fig. 1, (a) represents the cover in its 50 position of closely fitting the boiler and opening the valve, (e,)—(b,) is the boiler of common form. (c,) is the escape tube, as usually made; and (e,) is the valve. This valve is hinged or pivoted at (h,), and has 55 a winged portion, (f,) on the opposite side of the pivot, which comes into contact with the edge of the cover whenever the cover is depressed. The pressure of the cover upon this wing raises the valve; and when the 60 cover is removed, the preponderance of the weight of the valve over the winged portion, brings the valve down upon its seat, and closes the tube. The valve may be nicely 65 balanced, and made selfacting; but I find the present method of regulating the valve by the cover more reliable; and in fact it is infallible.

What I claim, therefore, is—

The employment of a valve, in combination with the escape tube of culinary boilers, such valve being controlled by the cover, or in any equivalent manner, substantially as herein set forth.

R. WM. BELSON.
